UNITED STATES PATENT OFFICE.

ERIC G. SHALKHAUSER, OF PEORIA, ILLINOIS.

DESIGN FOR A COMBINED RADIATOR, LAMP CASING, AND HOOD FOR MOTOR VEHICLES.

Application filed May 19, 1927. Serial No. 22,102. Term of patent 7 years.

To all whom it may concern:

Be it known that I, ERIC G. SHALKHAUSER, a citizen of the United States residing at Peoria, in the county of Peoria and State of Illinois, have invented a new, original, and ornamental Design for a Combined Radiator, Lamp Casing and Hood for Motor Vehicles, of which the following is a specification, reference being had to the accompanying drawing, forming part hereof.

Figure 1 is a front elevation of a combined radiator, lamp-casing and hood of a motor vehicle, showing my design.

Figure 2 is a plan of the same, showing the side of the hood extending directly from the rear edge of the lamp casings.

Figure 3 shows the combined radiator, lamp-casing and hood of my design, in perspective illustrating the curvature of the sides of the hood as extending rearwardly directly from the lamp casing, and

Figure 4 is likewise a perspective of the same showing parts in a different position to better show the design.

I claim:

The ornamental design for a combined radiator, lamp-casing, and hood for motor vehicles, as shown.

In testimony whereof I affix my signature.

ERIC G. SHALKHAUSER.
